UNITED STATES PATENT OFFICE.

VICTOR A. LANG, OF NORTH FORT WORTH, TEXAS.

GAGE-COCK.

1,214,326.

Specification of Letters Patent. Patented Jan. 30, 1917.

Application filed April 1, 1916. Serial No. 88,294.

To all whom it may concern:

Be it known that I, VICTOR A. LANG, a citizen of the United States, residing at North Fort Worth, in the county of Tarrant and State of Texas, have invented certain new and useful Improvements in Gage-Cocks; and I do hereby declare the following to be a full, clear, and exact description of the invention, such as will enable others skilled in the art to which it appertains to make and use the same.

This invention relates to new and useful improvements in a gage cock and one of its objects is the provision of a device of this character, which shall be simple, durable and efficient, and which may be manufactured and sold at a comparatively low cost.

Another object of this invention is to provide a valve seat, having beveled valve engaging surfaces or faces upon each side thereof, whereby the valve seat may be readily reversed when the valve engaging surface or face upon one side has become worn.

A further object of this invention is to provide a valve casing of a pair of sections and having the valve seat of such a construction that the pair of sections of the casing will hold the valve seat against accidental displacement.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a fragmentary front elevation of a feed boiler gage, illustrating my invention applied thereto. Fig. 2 is a longitudinal sectional view of my device, Fig. 3 is a similar view, illustrating a modified form of valve seat, and Fig. 4 is a detail sectional view illustrating the construction of the valve seat in the preferred form.

Referring in detail to the drawing, the numeral 1 indicates a valve casing, consisting of sections 2 and 3. The section 3 is provided with an enlarged squared portion 4, whereby the section may be gripped by a wrench. One end of the section 3 is pro-

vided with screw-threads 5 to be threaded within a steam boiler gage 6. The screw-threaded end of the section 3 is closed by a wall 7, having a plurality of openings 8. The other end of the section is internally screw-threaded to receive the screw-threaded end of the section 2. The section 2 is closed by a curved wall 9, having a suitable stuffing box 10 to slidably receive a valve rod 11. The section 2 of the valve casing is provided with an outlet port in which is threaded a nozzle 12. A bracket 13 is secured to the section 2 and has pivoted thereto, a handle 14, having an arm 15 formed thereon adapted to rest upon the end of the valve rod 11.

A valve head 16 is threaded to the inner end of the section 11 of the valve rod and is provided with beveled faces 17 and 18. The inner section 19 of the valve rod is threaded to the valve head and extends through a central opening in the wall 7. A coil spring 20 is mounted on the inner section 19 of the valve rod and bears against the wall 7 and the valve head 16.

A substantially circular valve seat 21 is provided with outer and inner beveled engaging surfaces or faces 22 and 23. The engaging surface or face 22 is adapted to rest upon inclined wall 24 formed on the section 3 of the valve casing. The other engaging surface or face 23 is adapted to bear against the inner beveled end of the section 2 when said section is screwed into the section 3, thus holding the valve seat 21 against movement. The spring 20 normally holds the beveled face 17 of the valve head 16 against the beveled engaging surface or face 23 of the valve seat 21. When the surface or face 23 becomes worn, the valve seat may be reversed and the oppositely disposed surface or face 22 will be engaged by the valve head 16. The valve head 16 may also be reversed when worn to bring the beveled face 18 into an engagement with the valve seat.

Referring to the modified form illustrated in Fig. 3, it consists of a valve casing constructed of sections 25 and 26 which are provided with their adjoining ends internally screw-threaded. The section 25 is closed at its outer end by a curved wall 27, having a suitable stuffing box 28 to slidably receive a valve rod 29, consisting of outer and inner sections. A bracket 30 is

secured to the section 25 of the valve casing and has pivoted thereto, a handle 31, having an arm 32 adapted to rest on the valve rod 29. A nozzle 33 is secured in the outlet 5 port in the section 25 of the valve casing adjacent the curved wall 27. The sections 25 and 26 are connected by a screw-threaded valve seat 34, having an annular flange 35 to space the ends of the 10 sections 25 and 26 apart. The valve seat 34 is provided with beveled engaging surfaces or faces 36 and 37 for the reception of a valve head 38. The valve head 38 is connected to the inner end of the outer section 15 of the valve rod and to the outer end of the inner section which extends through the wall 39 of the inner section 26 of the valve casing. The wall 39 is provided with a plurality of openings 40. The valve head 20 is provided with a beveled face 41 for engagement with the face 37, and for an engagement with the face 36 when the valve seat is reversed. A coil spring 42 normally holds the valve 38 into an engagement with 25 the valve seat. The section 26 of the valve casing is provided with an enlarged squared portion 43 to be received by a wrench for screwing said section into a steam boiler gage.

20 While I have shown and described the preferred embodiment of my invention, it will be understood that minor changes in construction, combination and arrangement of parts may be made without departing

from the spirit and scope of the invention 35 as claimed.

Having thus described my invention, what I claim is:—

A gage cock comprising a sectional casing, a reversible valve seat held between 40 the sections of said casing, a valve rod extending through one of the sections of said casing and having its inner end screw-threaded, a shoulder formed on said rod adjacent the screw-threaded end and having a beveled face, a valve head having a central screw-threaded bore having each end flared and beveled to engage the beveled face of the shoulder when threaded to the valve stem, said valve head having valve 50 seat engaging faces, a perforated wall closing one end of one of the casings, a valve rod 55 slideable in said wall and having one end threaded into the valve head, a shoulder formed on the last mentioned valve rod and having a beveled face to coöperate with the beveled face of the central bore of the valve head, a spring engaging the wall and the last mentioned shoulder to seat the valve head against the valve seat, and means for 60 operating the first mentioned valve rod.

In testimony whereof I affix my signature in presence of two witnesses.

VICTOR A. LANG.
